DESIGN FOR A SERVICE SHELF FOR BOWLERS

Andrew L. Henkel and Burke M. Ewing, Chicago,
Ill., assignors to The Brunswick-Balke-Collender
Company, Chicago, Ill., a corporation of Delaware

Application April 10, 1940, Serial No. 91,571

Term of patent 14 years

To all whom it may concern:

Be it known that we, Andrew L. Henkel and Burke M. Ewing, both citizens of the United States and both residing in the city of Chicago, in the county of Cook, State of Illinois, have jointly invented a new, original, and ornamental Design for a Service Shelf for Bowlers, of which the following is a specification, reference being had to the accompanying drawing, forming a part thereof.

In practice, the article is mounted as upon the outside of an end panel of a settee.

We claim—

The ornamental design for a service shelf for bowlers, as shown.

ANDREW L. HENKEL.
